O. STERN

MATRIX SETTING AND LINE CASTING MACHINE

Filed July 2, 1925

UNITED STATES PATENT OFFICE.

OTTO STERN, OF BERLIN, GERMANY, ASSIGNOR TO THE FIRM: STANDARD COMPOSITOR AKTIENGESELLSCHAFT, OF BERLIN, GERMANY.

MATRIX-SETTING AND LINE-CASTING MACHINE.

Application filed July 2, 1925, Serial No. 41,138, and in Germany February 14, 1924.

This invention relates to matrix-setting and line-casting-machines and more particularly to an indicating device for the casting wheel of such machines for indicating the temporary position of the mould or casting form relatively to the position of said casting wheel.

In matrix-setting and line-casting-machines having a casting wheel with a plurality of moulds thereon there is a disadvantage found therein, that the compositor is not at all times informed about the temporary position of the moulds relatively to their working position. It is therefore impossible for the compositor to give to the casting wheel that direction of rotation, which enables the new mould to be brought on the shortest way into its working position. For this purpose, according to the present invention, the machine is equipped with an indicating device, which enables the compositor at any time to read off the position of the several moulds relatively to the spout of the casting device, that is to say to read off the temporary working position of the former. In order to do away with this inconvenience, there have been proposed various arrangements, which, however, have not given a solution of this problem. Thus it has been proposed, to equip the casting wheel and the protecting cover placed above the same with differentiating marks, which were arranged in various ways and designated with numerals, in order to provide the desired indication without necessitating the vise to be opened. All devices and propositions of this kind, however, could not solve the difficulty, because the marks would be in proper position only during inoperative condition of the casting wheel and the position of the mould or casting form had to be ascertained according to the indicating mark by means of a special schedule or table provided for this purpose.

Preferably the indicating device according to this invention is combined with a second indicating device, which at the same time indicates the temporary position of the several magazines relatively to their working position. Indicating devices for the position of the magazines are known as individual devices. An object of this invention

is therefore, to provide a novel and advantageous combination of an indicating device for the position of the magazine with an indicating device for the position of the casting wheel, so that at a point which is centrally positioned with regard to the operator there will be an indication given at any time showing which of the moulds and magazines are temporarily in working position, and which other moulds, magazines or types are within the machine. In addition to this this combined indicating device will also show the place at which these devices are temporarily positioned. The operator will thus be enabled to adjust the types of every desired magazine relatively to every desired mould in the shortest possible way. This will result in a saving of time for the operator, thereby rendering the machine far more effective than has heretofore been possible.

In the drawing an example is shown of carrying this invention into effect, and more particularly in the above mentioned manner, whereby the positions of the moulds as well as of the magazines are indicated.

Referring now to the drawing, Fig. 1 is a front view of the assembled indicating device according to this invention, Fig. 2 a section through the indicating device in connection with the drive of the machine, said device serving for the indication of the position of the magazine and the adjusting means for the latter. Fig. 3 is a plan view, partly in section, of the driving means for the indication of the position of the mould, Fig. 4 a rear view of the device shown in Fig. 3, and Fig. 5 a top view of the cover plate of the indicating device. Fig. 6 is a segmentary sectional view taken on line 6-6 of Fig. 1.

In a bearing 1 forming part of the machine there is mounted a shaft 2 which carries a rotatable annular disc 3 having the form of a cogwheel at its circumference. This disc 3 furthermore carries at one of its sides the indicating marks 4 serving for the indication of the position of the moulds. The annular disc 5 is concentrically surrounded by said indicating marks 4 and is keyed to the shaft 2 to rotate in unison therewith. The annular disc 5 carries the indi-

cating marks 6 serving for the indication of the position of the magazine and is provided with driving means, which are described further below. The indicating means as a whole is closed up by the cover plate 7, which through windows 8 exposes the position of the indicating marks on the annular discs 3 and 5. The cover plate 7, for the purpose of permitting an easy 10 change thereof, is detachably mounted upon the annular member 9, which latter is fixed upon the frame of the machine.

The position of the mould will be shown by the annular disc 3 and the indicating 15 marks provided thereon. Each motion of the casting wheel 10 will cause the rotation of the gear 13 by means of the interposed gears 11 and 12, said gear 13 causing the rotation of the disc 15 by means of a pin 14. 20 The disc 15 is rigidly connected with the sprocket wheel 16 and the latter, by means of the chain 17, the sprocket wheel 18 and the gear 19 connected therewith, will thus adjust the annular disc 3 together with the 25 indicating marks 4 for indicating the position of the casting wheel.

In the arrangement shown in the drawing the casting wheel 10 is arranged for five moulds and, after the completed casting of a line, is rotated through a certain angle and brought into the ejecting position whereupon it is again rotated backward through the same angle into the casting position after the ejection of the line, 30 in case another casting form or mould shall not be brought just at this time into its working position. During this forward and backward rotation, which is the working rotation, the indicating device shall remain 35 unaffected, and this is accomplished by the above-mentioned driving means for the disc 15. The gear 13 carries a pin 14, which slides in a concentric groove of the disc 15, as shown in Fig. 4. The length of this 40 groove is so chosen, that during the working motion of the casting wheel said pin will freely slide within said groove, without, however, causing the disc 15 to be carried with said pin. The pin 14, on the other 45 hand, will carry the disc 15 with it, only after another mould has been adjusted and assumed its working motion. Said pin 14 will thus rotate the disc 3 together with the 50 indicating marks 4 in the manner above described. The disc 15 is provided with notches, as shown in Fig. 4, a pin 20 resiliently engaging said notches when in position of rest and thereby securing the driving means for the indicating marks against 55 unintended motion, such as may be caused by vibrations or the like. In the example as shown in Fig. 4 the disc 15 is provided with two notches for securing the position of rest, in accordance with the ratio of gear- 60 ing between the casting wheel and the disc

15, said ratio having a value of 5:2, as shown in the drawing. The braking device for the casting wheel, as shown in Fig. 3, does not form part of this invention and is therefore not further described. 70

The arrangement, as shown in the drawing, is intended for use with a casting wheel, which changes its direction of rotation during its working period, that is to say during the cycle of casting, ejecting and 75 again casting. If other forms of casting wheels shall be employed, which between each casting operation perform a full revolution in the same sense of rotation, the arrangement according to this invention is 80 preferably so modified, that the indicating device is connected not with the casting wheel itself but with the means for rotating the latter, such as for instance described in the specification of the U. S. Patent No. 85 725,861, according to which the crank or handle serving for the rotation of the casting wheel, instead of being actuated only during each adjustment while being otherwise uncoupled and in condition of rest, is 90 connected with the sprocket wheel 18 or the gear 19 in a proper ratio of transmission.

The adjusting device for the casting wheel, as above mentioned, is connected with an indicating device for the position of the 95 several magazines. In the arrangement as shown five magazines 21 are assumed, which when adjusted in operative position will rotate around the axis 22, Fig. 1. For this purpose the worm 23 is connected with the 100 shaft 2, whereby the segmental gear or rack 26 provided at the frame of the magazine, is adjusted by the aid of a segmental gear or rack 24 and a gear 25, as soon as the shaft 2 is rotated by means of the handle 105 27. The ratio of gearing between said handle and the adjustment of the magazine, which in the arrangement as shown has a 110 value of 6:5, is thereby so chosen, that the indicating disc 5 with the indicating marks 6, mounted upon the shaft 2, and rotating upon rotation of the handle 27 will cause in every position of the magazine another indicating mark to be exposed through the windows 8 in the cover plate 7. The position of the handle 27 will thus be a different one for each position of the magazine. In order to fix the handle the annular member 9 and the cover plate 7 are each provided with as many holes 28 as there are positions of rest for the handle or the magazines. The resiliently mounted crank-pin 30 will engage these holes and secure in this way the inoperative position of the handle and thereby the position of the magazine. The holes 28 serving for the fixing of the handle and of the magazines are preferably 115 properly designated in order to avoid confusion. 120

The exchange of the magazines is accom- 130

plished during inoperative position of the operating devices, that is after the segmental gear or rack 26 has swung the magazines to an extent, corresponding to one half the distance of the magazines from their working position. The ratio of gearing as chosen in the arrangement as shown, will cause the crank-pin 30 (Fig. 2) to engage one hole 28 in the annular member 9 for each average position of the magazine. In case another ratio of gearing is chosen, for instance a ratio having the value 7:5, it is preferable to employ more holes 29 in the annular member 9 and the cover plate 7, which holes permit the fixing of the crank-handle 27 while the magazines are in a position to be adjusted.

I claim:—

1. In a matrix-setting and line-casting machine, the combination of a casting wheel adapted to receive a plurality of moulds, a casting device associated with said casting wheel, and an indicating device connected to said casting wheel, said indicating device being adapted to indicate the temporary working positions of said casting wheel relatively to said casting device.

2. In a matrix-setting and line-casting machine, the combination of a casting wheel adapted to receive a plurality of moulds, a casting device associated with said casting wheel, an indicating device for indicating the temporary working position of said casting wheel relatively to said casting device including a plurality of designation marks, and actuating mechanism interposed between said casting wheel and said indicating device.

3. In a matrix-setting and line-casting machine, the combination of a casting wheel adapted to receive a plurality of moulds, a casting device associated with said casting wheel, an indicating device for indicating the temporary working position of said casting wheel relatively to said casting device and actuating mechanism between said indicating device and said casting wheel.

4. In a matrix-setting and line-casting machine, the combination of a casting wheel adapted to receive a plurality of moulds, a casting device associated with said casting wheel, an indicating device indicating the temporary working position of said casting wheel relatively to said casting device, and actuating mechanism interposed between said casting wheel and said indicating device, including a lost motion connection for maintaining the indicating device in an unaffected condition during the cycle of operation of said casting wheel.

5. In a matrix-setting and line-casting machine, the combination of a casting wheel adapted to receive a plurality of moulds, a casting device associated with said casting wheel, an indicating device for indicating

the temporary working position of said casting wheel relatively to said casting device, actuating mechanism between said indicating device and said casting wheel, and a second indicating device connected to the indicating device for the casting wheel, a plurality of magazines and driving means therefor, said second indicating device being operatively connected with said driving means for indicating the temporary position of said magazines relatively to their working position.

6. In a matrix-setting and line-casting machine, the combination of a casting wheel adapted to receive a plurality of moulds, a casting device associated with said casting wheel, an indicating device for indicating the temporary working position of said casting wheel relatively to said casting device, actuating mechanism between said indicating device and said casting wheel, a second indicating device connected to the indicating device for the casting wheel, a plurality of magazines and driving means therefor, said second indicating device being operatively connected with said driving means for indicating the temporary position of said magazines relatively to their working position, a cover plate provided with windows adapted to expose both of said indicating devices, said cover plate being provided with a set of holes corresponding to the working positions of said magazines, and locking means co-operative with said holes on said cover plate, said latter means being adapted to lock said driving means in each of the working positions of said magazines.

7. In a matrix-setting and line-casting machine, the combination of a casting wheel adapted to receive a plurality of moulds, a casting device associated with said casting wheel, an indicating device for indicating the temporary working position of said casting wheel relatively to said casting device, actuating mechanism between said indicating device and said casting wheel, a second indicating device connected to the indicating device for the casting wheel, a plurality of magazines and driving means therefor, said second indicating device being operatively connected with said driving means for indicating the temporary position of said magazines relatively to their working position, a cover plate provided with windows adapted to expose both of said indicating devices, said cover plate being provided with a set of holes corresponding to the working positions of said magazines, and locking means co-operative with said holes on said cover plate, said latter means being adapted to lock said driving means in each of the working positions of said magazines, said cover plate being further provided with a second set of holes thereon corresponding to the exchange position of the magazines, whereby said locking means will be actuated also during said

120
125
130

exchange position of the magazines for locking said driving means.

8. In a matrix-setting and line-casting machine, the combination of a plurality of 5 magazines, an indicating device therefor, a casting wheel, an indicating device for said casting wheel, said indicating devices having

associating indices for indicating the temporary working positions of said magazines with respect to the temporary working positions of said casting wheel. 10

In testimony whereof I have affixed my signature.

OTTO STERN.
